C. W. DALY

HOT PLATE AUTO COOKER

Filed June 30, 1925

INVENTOR.

Charles W. Daly,
BY
James J. Sheehan & CO ATTORNEYS.

UNITED STATES PATENT OFFICE.

CHARLES W. DALY, OF DAVENPORT, IOWA.

HOT-PLATE AUTO COOKER.

Application filed June 30, 1925. Serial No. 40,665.

My present invention pertains to hot plates for use in connection with the exhaust manifold of an internal combustion or similar type of engine and it contemplates the provision of a simple and inexpensive exhaust pipe having an integral portion thereon that is so constructed and arranged that the contents of pans may be readily and easily heated.

10 The invention further contemplates the provision of an exhaust manifold pipe that is adapted to be secured to the manifold so as to convey the heat elements to the hot plate.

15 Other objects and advantages of the invention will be fully understood from the following description and claim when the same are read in connection with the drawings accompanying and forming part of this specification in which—

Figure 1 is a plan view partially in section and showing my novel device attached to the engine block.

20 Figure 2 is a longitudinal sectional view taken on the plane indicated by the line 2—2 of Figure 1 and looking in the direction of the arrows.

Figure 3 is a similar view taken on a vertical transverse section and on the line 3—3 of Figure 1 and looking in the direction of the arrows.

Similar numerals of reference designate corresponding parts in all the views of the drawings.

25 My novel device is secured to the engine block E that is provided with the exhaust opening X, and the hot plate consists of the oval body portion having a top 1 and a bottom 2. The plate further comprises the end wall 3 and the upper and lower plates 1 and 2 are provided with the flanges 4 and adapted to secure the plate to the engine block are screws or other fastening means 5 that pass through the hole 6 of

the flanges 4. Arranged within the plates 45 1 and 2 is a baffle that is arcuate in construction and indicated by 7. This baffle plate 7 is cast integral with the body and also cast integral therewith is an exit 8 for final exhaust. It will be seen that the exit 8 extends downwardly in order to engage the rest of an exhaust pipe or extension that is generally employed with an internal combustion engine.

Secured to the end wall 3 are the upstanding lugs 9 that are perforated at 10 and in the practical use of the device I prefer to rest nesting pans 11 on the upper portion 1 of the oval body and these pans may be provided with the lid 12 that in turn is provided with the spring hooks 13 that engage the top 12 and are adapted to be hooked into the perforations 10 of the lugs 9.

I would distinctly have it understood that the device is adapted to be used in lieu of 65 the manifold at present in use on engines and that its attachment will in no way hinder the operation of the engine or the vehicle on which it is mounted, and that the heating of pans and the like may be 70 readily and easily accomplished.

Having described my invention, what I claim and desire to secure by Letters Patent is:—

An exhaust manifold adapted to serve as 75 a hot plate, said manifold comprising a hollow body portion of oval outline and having a flat top wall, said manifold having its rear end provided with an outlet opening and having one lateral wall provided immediately in front of said outlet opening with an inlet passage and equipped with attaching flanges, and a baffle in said manifold interposed between said inlet passage and said outlet opening.

80 85 In testimony whereof I have hereunto set my hand.

CHARLES W. DALY.
